FIG. 3

FIG. 4

FIG. 5

FIG. 6

FIG. 7

FIG. 1 is a front elevational view of a signboard panel embodying my new design;

FIG. 2 is a rear elevational view thereof;

FIG. 3 is a bottom plan view thereof;

FIG. 4 is a cross sectional view taken on line 4—4 of FIG. 1;

FIG. 5 is an enlarged cross sectional view taken on line 5—5 of FIG. 2;

FIG. 6 is an enlarged cross sectional view of a modified form of the signboard panel shown in FIG. 1 wherein the modification resides in the configuration of the peripheral frame; and

FIG. 7 is an enlarged cross sectional view of a second modified form of the signboard panel shown in FIG. 1 wherein the modification resides in the configuration of the peripheral frame.

I claim:

The ornamental design for a signboard panel, as shown and described.
